UNITED STATES PATENT OFFICE.

CONRAD JOBST, OF TOLEDO, OHIO, ASSIGNOR TO THE TOLEDO AUTOMATIC BRUSH MACHINE COMPANY, OF TOLEDO, OHIO, A CORPORATION OF OHIO.

WORK HOLDER FOR BRUSH MACHINES.

Application filed September 2, 1924. Serial No. 735,466.

The invention relates to brush machines of that type in which the bristle tufts are successively formed and deposited in previously drilled holes in the brush head and are secured therein by a staple. The invention has more particular reference to the means for adapting such machine to the manufacture of a specific type of brushes, viz, rotary brushes having a plurality of circumferential rows of tufts converging towards a common plane. The invention therefore consists in the construction of the work holding means and the cooperative combination of the same with the tuft setting and drilling means as hereinafter set forth.

In the drawings:

Figure 1 is a sectional elevation of a brush forming machine to which my improvements are applied;

20 Figure 2 is a transverse section thereof;

Figure 3 is a similar view taken on a different plane, partly in elevation;

Figure 4 is a cross section through Figure 3 substantially on line 4-4 thereof;

25 Figure 5 is an enlarged sectional elevation of a portion of Figure 1;

Figure 6 is a horizontal section through the product.

Figure 7 is a section on the line 7-7 of 30 Figure 4; Figure 8 is a section on the line 8-8 of Figure 5.

My improvements are applicable to any suitable construction of brush machine provided with tuft forming, depositing and stapling mechanism and which may or may not be associated with the drilling mechanism. As specifically shown, my improved work holder is designed to cooperate with the machine having associated tuft forming and head drilling mechanisms which operate simultaneously on pairs of heads. Inasmuch, however, as the specific construction of the tufting and drilling mechanism forms no part of the present invention, I have omitted showing the same in detail.

As shown, A is the tuft depositing nozzle which reciprocates in a horizontal plane, and B is a vertically reciprocating head forming a part of the tuft forming mechanism. The mechanism for reciprocating these members is shown diagrammatically

as including a crank shaft C, a pitman connection D between the crank and the nozzle, a bell crank lever E for actuating the head B and a link F for connecting said bell crank with the pitman D.

The type of brush to be manufactured comprises a cylindrical wooden head G centrally apertured at G' and having a plurality of rows of tufts G², G³, G⁴ and G⁵ extending outward from the periphery thereof and converging to a common central plane. It is therefore necessary to provide mechanism for drilling the brush heads G with tuft receiving apertures in the desired angular relation and also for presenting the drilled head in proper registration with the tuft depositing nozzle so as to successively fill the holes with tufts.

To accomplish this purpose a work holder 70 is provided for receiving the previously drilled brush heads, said holder being intermittently rotated to pass from tuft to tuft in the same row and being also angularly adjusted to correspond with the varying angles of the holes in the different rows. Preferably the same construction of holder is adapted to receive an undrilled blank and to similarly present the same to an associated drilling mechanism so at the completion of 75 each cycle one blank or head will be completely drilled and a previously drilled head will have been completely tufted.

In detail, H is a rock frame which is mounted in bearings I so that its axis lies 85 in the horizontal plane of the reciprocating nozzle A and at right angles to the direction of reciprocation. This rock frame has a portion H' offset from the axis of the frame and connecting the portions within 90 the opposite bearings I. The rock frame also has a depending arm W. J and J' are rock arms extending from opposite ends of the rock frame H and carrying at their free ends bearings K for rotary work supporting 95 spindles K'. These spindles extend in a plane which intersects a perpendicular plane passing through the axis H at a predetermined distance from said axis. This distance is such that when a brush head G is 100 mounted on the spindle K, its periphery will be spaced from the axis H by a distance

substantially equal to the length of the bristles. The head G is clamped against the shoulder K² on the spindle by a thumb screw K³ engaging a threaded end of the spindle, 5 and a dowel K⁴ on said shoulder K² engaging an aperture in the brush head will rotatively position the same.

Each of the spindles K' is rotatively driven through the medium of skew gears L, L', 10 respectively on said spindles and a transversely extending shaft L², the latter having a bearing in the depending arm W² of the rock frame H. The shaft L² in turn is rotatively driven through the medium of skew 15 gears M, M', shaft N and skew gears O, O' from a shaft P, which is coaxial with the frame H and rotatable therein. Q is a ratchet wheel fixed upon the shaft P and R, R', R², R³ are pawls engaging said ratchet 20 wheel and mounted upon the reciprocating head B. The arrangement is such that each reciprocation of the head B will rotate the ratchet wheel Q one or more notches, which through the connecting mechanism described 25 will rotate the spindles K' and the brush heads G mounted thereon. The amount of rotative advancement of the head in each step corresponds as to the distance between tufts in the brush and as both heads are advanced simultaneously and correspondingly, 30 one is positioned for boring while the other is positioned for the setting of a tuft. The step by step movement may thus continue until a full revolution of each brush head is 35 completed.

In addition to the step by step advancement the spindles of the rolls must be angularly adjusted in passing from one circular row of tufts to another. This is accomplished by a rocking of the frame H and this 40 in turn by the operation of a cam and co-operating mechanism. As specifically shown, the bearings I in which the frame H is journaled are on brackets T extending upward 45 from a table U. The cam S is located beneath the table and is actuated in timed relation to the crank shaft C by suitable mechanism, such as the intermittent gearing S', shaft S² and worm gearing S³. V is a rod 50 actuated by the cam S and slidably engaging bearings in the bracket T. W is a laterally projecting arm at the upper end of the rod V, which is slotted to engage a bearing W' secured to the rock arm W² of the rock 55 frame H by a pin W³. Thus when the parts are properly timed, the cam S will periodically raise or lower the rod V to rock the frame H into different angular positions. In each position of adjustment of said frame a 60 complete revolution of each brush head is effected by the step-by-step mechanism before described so that a circular row of holes are bored in one brush head and a circular row of tufts are set in the other head.

65 In the complete operation of the machine

the brush backs are engaged with the spindles K', are rotatively positioned thereon by the dowel pins K⁴ and are clamped by the nuts K³. One of these blanks, which has not been bored, is in registration with the boring machine (not shown) while the other blank previously bored has been transferred from the boring work holder to the tuft setting work holder. When the machine is started in operation, each reciprocation of 70 the nozzle A will deposit a tuft in one of the holes of the bored blank and during the return stroke of the nozzle the movement of the head B through the medium of the pawls R will actuate the ratchet wheel Q, revolving 75 the frame H and through the train of connected mechanism, rotatively adjusting each of the brush heads. Such operation is repeated until the circular row of tufts has been placed, at the completion of which the cam S raises or lowers the rod V to change 80 the angle of the spindles K'. Tufts are then successively set in a second circular row and so on until all of the rows for the heads are completed.

In the arrangement of successive rows of tufts it is usually desirable to stagger the holes. This is accomplished by providing a separate pawl for each row, said pawls R, R¹, R² and R³ being of different length so 85 as to register differently with the teeth of the ratchet wheel. To adjust the pawls into and out of engagement with the ratchet wheel, there is preferably provided an intermittently rotated shaft X carrying a series of cams X' for engaging the respective pawls. Each cam has a depressed portion X² for a portion of its circumference and a circular portion X³ for the balance. The cams are 90 so arranged on the shaft X that when the portion X² of one cam registers with the corresponding pawl the raised portions X³ of the other cams engage the other pawls and prevent the latter from engagement 95 with the ratchet wheel Q. The shaft X has 100 mounted thereon a pinion Y, which is in mesh with the segmental gear Y' secured to the rock frame H, the arrangement being such that in different positions of adjustment of said rock frame the cams X' 105 will successively engage one of the pawls and will disengage the remainder thereof. Thus the amount of staggering of the holes in different rows is governed by the relative lengths of the pawls brought into engagement with the ratchet wheel Q. As shown in Figures 5 and 8, the pawl R is in engagement with the ratchet wheel Q because the depressed portion X² of the co-operating cam X' is in engagement with said 110 pawl R. The other pawls R', R² and R³ are all held out of engagement with the ratchet wheel because the respective cams 115 co-operating therewith have the raised portions X³ engaging the same. When the rock 120 frame is rotated the pawls R', R² and R³ will successively engage the ratchet wheel Q. The cam X' will then rotate the pawl R out of engagement with the ratchet wheel Q and the pawls R', R² and R³ will 125 engage the ratchet wheel. The cam X' will then rotate the pawl R' out of engagement with the ratchet wheel Q and the pawls R, R² and R³ will engage the ratchet wheel. The cam X' will then rotate the pawl R² out of engagement with the ratchet wheel Q and the pawls R, R' and R³ will 130 engage the ratchet wheel. The cam X' will then rotate the pawl R³ out of engagement with the ratchet wheel Q and the pawls R, R', R² and R³ will engage the ratchet wheel.

frame H is oscillated to adjust the work holder for another circular row of bristles, the gear segment Y' rotates the pinion Y and brings the depressed portion X' of another of the cams into engagement with its corresponding ratchet pawl and this pawl thereupon engages the ratchet wheel Q while the remaining pawls are held out of engagement.

10 The brush, which is the product of the operation just described, will have its bristles conically arranged and converging towards the central plane of rotation as shown in Figure 6.

15 What I claim as my invention is:

1. In a brush machine, a work holder mounted for rotative adjustment about transverse axes, means for adjusting said holder step-by-step about one of said axes 20 through a plurality of revolutions, and means operating automatically between successive revolutions in timed relation to said first mentioned means for adjusting said holder step-by-step about the other of said 25 transverse axes.

2. In a brush machine, the combination with means for performing successive operations upon the work, of a work holder mounted for rotative adjustment about

30 transverse axes, means actuated intermediate each operation upon the work for adjusting said holder step-by-step about one of said axes and continuing through a plurality of revolutions, and means for automatically adjusting said holder about the other of said transverse axes, one step between each successive revolution of said first-mentioned means.

35 3. In a brush machine, a work holder comprising a supporting frame, a rock shaft journaled thereon, a rock arm on said rock shaft, a spindle mounted in said rock arm with its axis transverse to the axis of said shaft and radially spaced therefrom, means for clamping a brush head upon said spindle, means for performing successive operations upon the brush head reciprocating in a plane of the axis of said rock shaft, means for rotatively advancing said spindle step-by-step 45 intermediate successive reciprocations of said means for performing operations on the brush head and through a plurality of successive revolutions, and means for rotatively adjusting said rock shaft step-by-step intermediate successive revolutions.

50 4. In a brush machine, the combination with a reciprocating means for performing successive operations, of a work holder comprising a frame, a rock shaft journaled therein, a rock arm on said rock shaft, a spindle journaled in said rock arm extending transverse to the axis of said rock shaft and radially spaced therefrom, means for clamping a brush head upon said spindle 55 with its central plane of rotation passing

through the axis of said rock shaft, means for intermittently rotatively advancing said spindle step-by-step through a plurality of successive revolutions, means for intermittently adjusting said rock shaft step-by-step, 70 one step between each successive revolution, and means for rotatively adjusting said spindle at the beginning of a revolution whereby the step-by-step movements are offset with relation to those in the preceding revolution. 75

5. In a brush machine, the combination with a reciprocating member for performing successive operations on the work, of a work holder comprising a frame, a rock shaft journaled therein, a pair of rock arms on 80 said rock shaft, a spindle journaled in each rock arm having its axis transverse to the axis of said shaft and radially spaced therefrom, means for mounting the work head upon said spindle with its central plane of 85 rotation passing through the axis of said shaft, and means for simultaneously and correspondingly rotatively adjusting said spindles to actuate said work heads step-by-step through a plurality of successive revolutions, and means for rotatively adjusting said rock shaft step-by-step, one step intermediate each successive revolution. 90

6. In a brush machine, the combination with a reciprocating means for performing successive operations, of a work holder comprising a frame, a rock shaft journaled therein, a rocker arm on said rock shaft, a spindle journaled in said rocker arm extending transversely to the axis of said rock 100 shaft and radially spaced therefrom, means for clamping a brush head upon said spindle with its central plane of rotation passing through the axis of said rock shaft, means for intermittently rotatively advancing said 105 spindle step-by-step comprising a ratchet wheel concentric with said rock shaft, transmission mechanism between said ratchet wheel and spindle, a plurality of pawls mounted on said reciprocating means adapted for alternative engagement with said ratchet wheel and offset in relation to each other, means for intermittently adjusting said rock shaft step-by-step between successive revolutions of said spindle, and means 110 operated by said adjustment of said rock shaft for successively engaging said pawls with said ratchet wheel, whereby the step-by-step rotative advancements of said spindle in successive revolutions are offset in 115 relation to each other.

7. In a brush machine, a work holder mounted for rotation through a complete revolution, a ratchet wheel connected thereto, a series of ratchet pawls of different 120 lengths engageable with said ratchet wheel, means for reciprocating said pawls, and means allowing one pawl to engage said ratchet wheel and preventing engagement of the remaining pawls. 130

8. In a brush machine, a work holder mounted for rotation through a complete revolution, a ratchet wheel connected thereto, a series of ratchet pawls of different lengths engageable with said ratchet wheel, means for reciprocating said pawls, means allowing one pawl to engage said ratchet

wheel and preventing engagement of the remaining pawls, and means for successively engaging the ratchet pawls with said ratchet wheel after predetermined reciprocations thereof. 10

In testimony whereof I affix my signature.
CONRAD JOBST.
